UNITED STATES PATENT OFFICE

FREDERICK J. SCHUMACHER, OF LOS ANGELES, CALIFORNIA

BURRING MACHINE

Application filed January 10, 1928. Serial No. 245,792.

This invention relates to devices used for burring sheet metal.

One of the objects of this invention is to provide a device by which a piece of sheet metal can be centralized quickly and securely.

Another object is to provide a device whereby a centralized piece of material is rotatably mounted.

Another object is to provide a supporting roller and burring roller mounted in a frame and operatively interconnected to be actuated in unison.

Another object is to provide a burring mechanism with its principal axis radially in relation to a rotating holder by which a piece of material disposed and rotated by the holder may be burred along its edge by means of the radially disposed burring mechanism.

Another object is to arrange a supporting roller and a primary burring roller swingably interconnected whereby the burring roller may be moved to a point spaced from the supporting roller to allow an insertion of a piece of material to extend with its edge beyond the edge of the supporting roller and so that the burring roller may be pressed sidewise against the edge of such inserted material in order to bend the edge over the edge of the supporting roller.

Another object is to provide a cooperating secondary burring roller whereby a bent-over edge of a piece of material can be burred down by moving the secondary burring roller radially against the edge of the material.

Other objects will appear from the following description and appended claims as well as from the accompanying drawing, in which—

Fig. 1 is a side elevation of a burring apparatus illustrating a rotating holder and burring rollers arranged according to this invention.

Fig. 2 is a top plan view of the burring apparatus illustrated in Fig. 1, showing the secondary burring roller mounted sidewise of the other burring roller, the secondary burring roller to be moved radially in relation to the rotating holder, and the primary bur-

ing roller movable across the edge of an inserted material parallel to the axis of the rotating holder.

Fig. 3 is a fragmentary detail longitudinal cross section of the secondary burring roller 55 with its operating mechanism.

Fig. 4 is a detail side elevation of the secondary burring roller.

Fig. 5 is a fragmentary detail end elevation of the clamping mechanism for the rotating 60 holder.

Fig. 6 is a fragmentary detail longitudinal section illustrating the operating and adjusting mechanism for the primary burring 65 roller.

Fig. 7 illustrates a piece of metal or sheet material with its edge bent over the edge of a supporting roller and with the primary burring roller resting on top of the material to illustrate the manner in which the primary burring is accomplished.

Fig. 8 illustrates a piece of sheet material clinched over the edge of a supporting roller with the secondary burring roller in a position to show how the burring is completed by 75 the action of the secondary burring roller.

Fig. 9 is a detail perspective view of a yielding centralizing roller.

In connecting sheet metal or any other sheet material, the edges of a flange or bottom plate to be connected to a cylindrical or hollow body of any other shape are generally bent or rolled over to bring the material along the edges practically folded upon itself, so that this folded-in edge of a flange 85 or bottom plate may be clinched over an outwardly bent or burred edge of a cylindrical or otherwise hollow body.

In Fig. 1, for instance, a piece of sheet material 9 is illustrated as placed between 90 the holding plates 10 and 11 with its edge indicated at 12 extending over the edge of the supporting roller 13 to a point below the primary burring roller 14.

In Fig. 7 a portion of a piece of sheet material is illustrated between the edge of the supporting roller 13 and the primary burring roller 14. The burring roller is provided with a flange portion 15 in a position 95 to press the edge of the material over the 100

edge of the supporting roller when the burring roller 14 is moved towards the supporting roller, so that the edge 16 of the inserted material 9 can be bent over in the manner illustrated in this figure. The cylindrical face 17 of the burring roller 14 serves to press the inserted material against the face of the supporting roller which in turn serves to produce frictional contact with the material to rotate the material through the rotating movement of the burring and supporting roller. The supporting roller 13 is, for this reason, preferably provided with a knurled or some suitable gripping face indicated at 18 to prevent a slipping of the inserted material when the burring roller 14 is moved so as to press the inserted material against the face 18. This frictional contact is used to maintain a rotating movement with the inserted material for the last action to finish the burring of the edge.

The finishing of the burring of the edge of the inserted material is accomplished by a second burring roller movable in a radial direction in relation to the inserted material. This finishing is best understood by the illustration in Fig. 8. By moving the second burring roller 19 against the already bent-over edge of the inserted material, the bent-over edge 16 is folded upon itself as the notched burring roller 19 closes in upon this edge of the inserted material, so that the finished burring has the appearance illustrated in this figure.

For rotatably supporting any inserted flange of sheet metal or sheet material, the two holding plates 10 and 11 are mounted centrally as indicated at 20, the lower plate on a pin mounted in the arm 21 of the frame 22, and the upper plate 17 mounted on a pin 23 in the arm 24 of the frame 22.

The plates 10 and 11 can be moved towards and away from each other by the action of a cam illustrated in Fig. 5. The pin 23 on which the plate 11 is pivotally mounted, is shiftably disposed in the arm 24 of the frame 22 to allow an axial movement of this pin 23 and therewith a movement of the plate 11 towards the plate 10 in the direction of the arrow 25. A cotter pin 26 serves to hold the spring 27 against the shoulder 28 in the arm 24. The spring presses the pin 23 normally and automatically against the cam 29.

By an actuating of the lever 30, the shaft 31 and therewith the cam 29 may be rotated to press upon the pin 23 against the pressure of the spring 27 to move the pin and therewith the supporting plate 11 in the direction of the arrow 25. The cam 29 is moved to 60 wedge against the end of the pin 23 sufficiently to hold the plate 11 pressed towards the plate 10 and when a piece of sheet material is disposed between the plates 10 and 11, this piece of material is sufficiently held between the plates to be rotated with the plates.

In Fig. 1, for instance, a piece of material 9 is inserted between the holding plates 10 and 11 with its edge extending beyond the edge of the supporting roller 13, below the burring roller 14, as indicated at 12.

To assure a proper centralizing of a round plate of sheet material, adjustable guiding rollers are provided as illustrated in Fig. 2, indicated at 32 and 33. By setting these guiding rollers, smaller or larger plates can be inserted to be automatically centralized and turned about the axis concentric with the centers 20 of the holding plates 10 and 11. Either the frame 22 is made movable towards the frame 34, or the frame 34 is made movable towards the frame 22; so that any centralizing of material between the plates 10 and 11 brings the edge of such inserted material in proper relation to the supporting roller 13 and burring roller 14.

The secondary burring roller, illustrated in detail in Fig. 4, is notched in a peculiar way to facilitate a desired burring. A top flange 35 is formed in this secondary burring roller 19, having a smooth underside 36 against which the top surface 37 of an inserted material may rest. The opposite face of the lower flange 38 is first generally slanted in a downward direction, indicated at 39. In addition to this, the slanting face 39 is concaved or cut out, as indicated at 40. The lower edge 41 of this curved or grooved recess 40 is in a position to allow the lower edge 42 of the already bent material to slide in between the smooth surface 36 of the upper flange 35 and the lower edge 41. Since the bent edge of the inserted material rests on the sharp edge of the supporting roller 13, a pressing or moving of the secondary roller 19 against the bent edge of the inserted material results in a gradual curving of the bent edge 42 as this bent edge gradually slants over and into the curved groove 40 in the slanting face 39 of the lower flange 38 of the secondary burring roller 19.

The secondary burring roller 19 is normally held in inoperative position under the tension of the spring 43, as illustrated in detail in Fig. 3. A lever 44 engages the shouldered end 45 of the pin 46 carrying the burring roller 19. The spring is inserted into the housing 47 to rest with one end against the shoulder 48, while the pin 49 rests against the opposite end of the spring. By moving the lever in the direction of the arrow 50 against the tension of the spring 43, the burring roller can be brought to bear against the edge of an inserted material in the manner described above.

An inserted material is, therefore, first placed in a flat condition between the holding plates 10 and 11. The primary burring roller is then moved towards the supporting roller 13 by means of the movable frame portion 51 pivotally mounted at 52 on the main

frame 34, and as soon as the edge of the material is bent down in the form illustrated in Figs. 4 and 7, the secondary roller is moved against this bent edge of the inserted material radially in the manner set forth above.

The moving of the pivotally connected frame portion 51 is accomplished by the mechanism illustrated in detail in Fig. 6. 10 The swingable frame portion 51 is held in its inoperative position by the tension of the spring 53. A set screw 54 threadedly disposed through the stationary portion 55 of the main frame 34 may be moved to press 15 the swingable frame 51 and therewith the burring roller 14 towards the supporting roller 13 in the manner set forth above.

The supporting roller 13 is mounted on a shaft 56 with its axis in a slanting direction 20 in relation to the axis 20 of the holding plates 10 and 11 and at the same time slanting in a radial direction in relation to the holding plates 10 and 11.

The burring roller 14 is mounted on a shaft 57 with its axis disposed in a radial direction in relation to the supporting plates 10 and 11.

The shaft 56 is geared at 58 to the shaft 59 which in turn is geared at 60 to the shaft 25 57. A pulley 61 serves through this gearing to actuate the several shafts and thereby the supporting roller 13 and the burring roller 14 in unison.

Since a slight unevenness in its circular 30 periphery of any inserted material might be the cause of undue friction, the centralizing rollers 32 and 33 are preferably made yieldable as illustrated more clearly in detail in Fig. 9.

40 The clamping base 62 serves to hold the rollers 32-33 on the main frame structure. The base may be adjustably set on the main frame 22 by the adjusting screw 63. The roller 32 or 33 is swingably mounted around the pin 64 held under tension within the frame 45 65 by the spring 66. Another set screw 67 serves for finer adjustments while the set screw 63 may be used for approximately adjusting the base 62 with the rollers near the edge of an inserted plate or material. The finer adjustment screw 67 is then set to assure a more accurate centralizing.

The rollers 32-33 are set so that the pressure of the edge of the inserted material may 50 act on the roller in the direction of the arrow 68, so that any unevenness along the edge of the inserted material may be able to pass the roller by acting against the tension of the spring 66 swinging the roller with the frame 65 around the pivot 64.

Having thus described my invention, I claim:

1. In a burring machine, cooperating holding members rotatable around a common 65 axis and movable towards each other, con-

trolling means for releasably moving the said members towards each other, a supporting roller disposed beyond the outer periphery and with its axis in a radial direction in relation to and inclined to the plane of said holding members, and a burring roller operatively connected with said supporting roller and disposed in a direct radial direction in relation to said holding members and adapted to move towards the supporting 70 roller.

2. In a burring machine, holding members mounted to rotate around a common axis and having engaging faces opposite and movable towards each other, a supporting roller disposed beyond the outer periphery of the holding members with its axis in a slanting direction in relation to the axis of the holding members and also slanting in a radial direction in relation to the holding members, the 80 roller having a conical face in alignment with the engaging face of one of the holding members, and a burring roller disposed with its axis in a radial direction in relation to the holding members and movable towards the 85 supporting roller.

3. In a burring machine, holding members mounted to rotate around a common axis and having engaging faces opposite and movable towards each other, a supporting roller disposed beyond the outer periphery of the holding members with its axis in a slanting direction in relation to the axis of the holding members and also slanting in a radial direction in relation to the holding members, the 90 roller having a conical face in alignment with the engaging face of one of the holding members, and a burring roller disposed with its axis in a radial direction in relation to the holding members and movable towards the 95 supporting roller.

4. In a burring machine, holding members mounted to rotate around a common axis and having engaging faces opposite and movable towards each other, a supporting roller disposed beyond the outer periphery of the holding members with its axis in a slanting direction in relation to the axis of the holding members and also slanting in a radial direction in relation to the holding members, the roller having a conical face in alignment with the engaging face of one of the holding members, and a burring roller disposed with its axis in a radial direction in relation to the holding members and movable towards the 110 supporting roller, the burring roller having a cylindrical portion to co-act with the slanting face of said supporting roller and having a flange-like portion adapted to move past the outer edge of the supporting roller 115 whereby a burring of material can be produced when disposed between the holding members to extend over the edge of said supporting roller.

5. In a burring machine, holding members mounted to rotate around a common axis and having engaging faces opposite and movable towards each other, a supporting roller disposed beyond the outer periphery of the holding members with its axis in a slanting direction in relation to the axis of the holding members and also slanting in a radial direction in relation to the holding members, the roller having a conical face in alignment with the engaging face of one of the holding members, and a burring roller disposed with its axis in a radial direction in relation to the holding members and movable towards the 120 supporting roller, the burring roller having a cylindrical portion to co-act with the slanting face of said supporting roller and having a flange-like portion adapted to move past the outer edge of the supporting roller 125 whereby a burring of material can be produced when disposed between the holding members to extend over the edge of said supporting roller.

ing face of said supporting roller and having a flange-like portion adapted to move past the outer edge of the supporting roller whereby a burring of material can be produced when disposed between the holding members to extend over the edge of said supporting roller, the said cylindrical portion of the burring roller adapted to co-act with the slanting face of the supporting roller for firmly engaging inserted material in order to rotate the material with the holding members.

5. In a burring machine, holding members mounted to rotate around a common axis and having engaging faces opposite and movable towards each other, a supporting roller disposed beyond the outer periphery of the holding members with its axis in a slanting direction in relation to the axis of the holding members and also slanting in a radial direction in relation to the holding members, the roller having a conical face in alignment with the engaging face of one of the holding members, a burring roller disposed with its axis in a radial direction in relation to the holding members and movable towards the supporting roller, the burring roller having a cylindrical portion to co-act with the slanting face of said supporting roller and having a flange-like portion adapted to move past the outer edge of the supporting roller whereby a burring of material can be produced when disposed between the holding members to extend over the edge of said supporting roller, the said cylindrical portion of the burring roller adapted to co-act with the slanting face of the supporting roller for firmly engaging inserted material in order to rotate the material with the holding members, and a secondary burring roller mounted sidewise of the first-named burring roller for a movement in a plane parallel to the engaging faces of the holding members adapted to be forced against the already bent edge of inserted material for a further burring while the material is rotated between the first-named burring roller and said supporting roller, and operating means for actuating the supporting roller and first-named burring roller.

6. In a burring machine, holding members rotatable around a common axis and movable towards each other, controlling means for releasably moving the said members towards each other, a supporting roller disposed beyond the outer periphery and with its axis in a slanting radial direction in relation to and inclined to the plane of said holding members, a burring roller operatively connected with said supporting roller and disposed in a direct radial direction in relation to said holding members and adapted to move towards the supporting roller, and centralizing rollers movable in a plane transversely to the axis of the holding members whereby inserted material can be centralized preparatory to being engaged between the holding members.

7. In a burring machine, cooperating holding members rotatable around a common axis and movable towards each other, controlling means for releasably moving the said members towards each other, a supporting roller disposed beyond the outer periphery and with its axis in a radial direction in relation to said holding members, a burring roller operatively connected with said supporting roller and also disposed in a radial direction in relation to said holding members and adapted to move towards the supporting roller, and centralizing rollers with their periphery movable in a plane transversely to the axis of the holding members whereby inserted material can be centralized preparatory to being engaged between the holding members, the centralizing rollers being mounted pivotally and yieldably whereby an inserted material may pass the rollers without undue friction regardless of unevenness along the edges of the inserted material.

8. In a burring machine, cooperating holding members rotatable around a common axis and movable towards each other, controlling means for releasably moving the said members towards each other, a supporting roller disposed beyond the outer periphery and

whereby a burring of material can be produced when disposed between the holding members to extend over the edge of said supporting roller, the said cylindrical portion of the burring roller adapted to co-act with the slanting face of the supporting roller for firmly engaging inserted material in order to rotate the material with the holding members, a secondary burring roller mounted sidewise of the first-named burring roller for a movement in a plane parallel to the engaging faces of the holding members adapted to be forced against the already bent edge of inserted material for a further burring while the material is rotated between the first-named burring roller and said supporting roller, and operating means for actuating the supporting roller and first-named burring roller.

9. In a burring machine, cooperating holding members rotatable around a common axis and movable towards each other, controlling means for releasably moving the said members towards each other, a supporting roller disposed beyond the outer periphery and with its axis in a slanting radial direction in relation to and inclined to the plane of said holding members, a burring roller operatively connected with said supporting roller and disposed in a direct radial direction in relation to said holding members and adapted to move towards the supporting roller, and centralizing rollers movable in a plane transversely to the axis of the holding members whereby inserted material can be centralized preparatory to being engaged between the holding members.

10. In a burring machine, cooperating holding members rotatable around a common axis and movable towards each other, controlling means for releasably moving the said members towards each other, a supporting roller disposed beyond the outer periphery and with its axis in a radial direction in relation to said holding members, a burring roller operatively connected with said supporting roller and also disposed in a radial direction in relation to said holding members and adapted to move towards the supporting roller, and centralizing rollers with their periphery movable in a plane transversely to the axis of the holding members whereby inserted material can be centralized preparatory to being engaged between the holding members, the centralizing rollers being mounted pivotally and yieldably whereby an inserted material may pass the rollers without undue friction regardless of unevenness along the edges of the inserted material.

11. In a burring machine, cooperating holding members rotatable around a common axis and movable towards each other, controlling means for releasably moving the said members towards each other, a supporting roller disposed beyond the outer periphery and

with its axis in a radial direction in relation to said holding members, a burring roller operatively connected with said supporting roller and also disposed in a radial direction in relation to said holding members and 5 adapted to move towards the supporting roller, centralizing rollers with their periphery movable in a plane transversely to the axis of the holding members whereby inserted material can be centralized preparatory to being engaged between the holding members, the centralizing rollers being mounted pivotally and yieldably whereby an 10 inserted material may pass the rollers without undue friction regardless of unevenness along the edges of the inserted material, and separate clamping frame structures for the centralizing rollers adapted to be set and 15 adjusted in a plane radially to the holding members.

10. In a burring machine, cooperating holding members rotatable around a common axis and movable towards each other, controlling means for releasably moving the said 20 members towards each other, a supporting roller disposed beyond the outer periphery and with its axis in a radial direction in relation to said holding members, a burring roller operatively connected with said supporting roller and also disposed in a radial direction in relation to said holding members and adapted to move towards the supporting roller, centralizing rollers with their periphery movable in a plane transversely to the 25 axis of the holding members whereby inserted material can be centralized preparatory to being engaged between the holding members, the centralizing rollers being mounted pivotally and yieldably whereby an 30 inserted material may pass the rollers without undue friction regardless of unevenness along the edges of the inserted material, and separate clamping frame structures for the centralizing rollers adapted to be set and adjusted in a plane radially to the holding 35 members and embodying secondary means for finer adjustments of the rollers with respect to their pivotal mountings.

40 In testimony that I claim the foregoing as my invention I have signed my name.

45 **FREDERICK J. SCHUMACHER.**
